[57] CLAIM

The ornamental design for a window vent, as shown.

DESCRIPTION

FIG. 1 is a perspective view of a window vent showing my new design, it being understood that the fragmentary portion of the automobile that is shown in broken lines is for illustrative purposes only;

FIG. 2 is an enlarged side elevational view thereof;

FIG. 3 is a greatly enlarged sectional view taken on the lines 3—3 of FIG. 2; and

FIG. 4 is a greatly enlarged fragmentary elevational view taken in the direction of the lines 4—4 of FIG. 3.
